ATTORNEY.

UNITED STATES PATENT OFFICE.

LUIGI MARTIGNONI, OF GENOA, ITALY.

THERAPEUTICAL APPARATUS.

Application filed January 18, 1924. Serial No. 687,136.

The present invention relates to electric therapeutic apparatus and has for its object to provide a portable apparatus for generating low frequency and high tension electric currents for therapeutic purposes, said apparatus also including means supporting the patient undergoing treatment, and means for applying the electric currents to the patient.

10 In the accompanying drawing wherein an approved embodiment of the invention is illustrated:

Figure 1 is a diagrammatic view of the electric circuit comprising the apparatus.

15 Figure 2 is a perspective view of the invention applied to use.

The apparatus hereinafter described is adapted for use with alternating current whereby to facilitate the utilization of a 20 transformer, but it will be readily understood that with a suitable current interrupting device, direct current may be utilized for the purpose.

25 Referring to the drawing in detail, the numeral 3 indicates a casing adapted to house the electrical apparatus and 4 is a single pole connector through which current from the apparatus is conducted to the conductor 5, through electrical connections of the blanket or cover, the latter being adapted 30 to overlie a patient, reclining upon a chair or other suitable support. The chair is formed of material having a requisite degree of electrical resistance to high tension current to which the patient is subjected.

35 The circuit illustrated in Fig. 1 includes two electrical connectors 13 and 13' in the form of sockets or the like adapted to selectively receive plugs (not shown) having 40 contacts connected with a suitable feed circuit.

The transformation of the ratio of the system is usually 1:240 and the voltages commonly used in the secondary for currents 45 of a frequency of 50 cycles are generally as follows:

	Volts.
For cures of nervous diseases	12,250
For recharge diseases	14,700
For infective diseases	17,900

During the use of the apparatus, contacts of the connectors 13 and 13' which are not connected with the feed circuit are bridged so as to permit the current to flow from one 55 contact to another.

The current from the connector 13 passes through the fuse 15 to the adjustable resistances 16 and through the control switches 17 and 17', the second adjustable resistance 16' through the other fuse 15', bridged connector 13' to the primary winding 11 of the transformer 19 through the conductor 18. The terminal of the primary winding 11 to which the conductor 18 is attached, is connected to the core of the transformer 19 and the convolutions of said winding 11 are arranged in groups, the several groups being connected respectively by conductors 20, 21 and 22 with movable contact elements 20', 21' and 22', the latter being adapted to be thrust into engagement with a contact bar 23, connected by a conductor 24 with an ammeter 25 which latter is connected by a conductor 26 with the circuit connector 13. Various lengths of the primary winding 11 may be connected in the circuit by actuation of the proper movable contact elements 20', 21' or 22'.

The secondary winding 12 of the transformer is also connected to the transformer core 19 at the point 27 and the other end 28 thereof is connected by a conductor 29 with the connector 4 on the casing 3, the current being conducted by the connector 4 to the blanket or cover through the conductor 5.

The cover is preferably constructed of two rubberized or waxed fabric sheets arranged one above the other and having arranged therebetween, a suitable flexible conductor which is connected with the terminal of the conductor 5.

What I claim is:

1. An apparatus of the character described adapted for supplying low frequency and high tension electrical currents for therapeutic purposes comprising a casing, an electric circuit arranged in said casing, said circuit including a current connector, independently operable switches adapted to separately control said circuit and arranged on opposite sides of the casing, a transformer including primary and secondary windings, said primary winding being interposed in said circuit, one end of each winding being grounded on the core of said transformer, and the other end of the secondary winding being adapted for connection with a conductor for applying electrical currents to a patient.

2. An apparatus as claimed in claim 1

- characterized by the provision of fuses interposed in said circuit.
3. An apparatus as claimed in claim 1 characterized by the provision of a cover including insulating layers, and a conductor arranged between said layers and connected with said single pole connector.
4. An apparatus as claimed in claim 1 characterized by the provision of means for variably controlling the energization of the primary winding of the transformer.
- In testimony whereof I hereunto affix my signature.

LUIGI MARTIGNONI.
